UNITED STATES PATENT OFFICE.

LIONEL H. HEYNEMANN, OF SAN FRANCISCO, CALIFORNIA.

SAFETY APPLIANCE FOR ELEVATORS.

SPECIFICATION forming part of Letters Patent No. 269,855, dated January 2, 1883.

Application filed June 25, 1880. (No model.)

To all whom it may concern:

Be it known that I, LIONEL H. HEYNEMANN, of the city and county of San Francisco, State of California, have invented a new and useful Improvement in Safety Appliances for Elevators, of which the following is a specification.

Nearly all safety appliances for elevators depend on springs held in place by the strain on the elevator-cable. These springs not alone lose their power in time, but are prevented from acting if parts of the hoisting machinery break, compelling the cable to turn the drum and sheave. In this case the friction is so great that the strong strain brought on the cable prevents the springs from acting on the safety device and the elevator is hurled to the ground. Another objection is that they do not act immediately when the cable breaks, but depend on the elevator acquiring a certain velocity before they will work. All devices supplied with centrifugal governors share this defect.

The object of my invention is to be perfectly independent of the cable, and to act immediately.

Similar letters of reference indicate corresponding parts.

Figure 1 shows a general view of the elevator with safety device attached. Fig. 2 shows a longitudinal section of the safety device. Fig. 3 shows a cross-section of gear-wheel; Fig. 4, a section of the valve.

A represents the ways upon which the carriage B moves up and down. To the ways are attached the rack C, with which a small gear-wheel, D, engages. This gear-wheel consists of several parts; (shown in Figs. 2 and 3:) an outside ring, a, with teeth, the center pin, b, and the rollers c. The center pin, b, has noses cut on its surface. (Only shown in Fig. 2.) When the elevator ascends the teeth of the ring a engage in the rack C, and the ring a glides over the rollers c, that rest against the noses of the center pin without turning it. When it descends the ring a, revolving the opposite way, forces the rollers away from the noses and wedges them in between the outer ring and the surfaces of the center pin, causing it to revolve. To this center pin is keyed an arm, E. To this arm is attached the piston-rod G of a small cylinder, H. This cylinder is filled with

any fluid—for instance, oil. The two ends of this cylinder are connected by a channel, I.

The action of the device is as follows: When the elevator ascends the ring a revolves without bringing any other parts into operation. When it descends the center pin, b, turns with it the arm E, and the piston L forces the oil from one side of the piston through the channel I to the other side. The resistance thus offered to the piston is the essential part of my safety device. This resistance can be varied at will by the valve shown on a larger scale by Fig. 4. A sleeve, f, having an opening, g, on each side and an opening, o, at the bottom 65 on one side, is screwed into the cylinder in such a manner that the openings g form a continuation of the channel I. This sleeve contains a screw, m, under that a spring, l, and below that a round stopper, h, turned smooth, so that 70 it can glide up and down in the sleeve. This stopper has an opening, k, and a small pin, p, screwed into its foot. Through the holes r oil is supplied from time to time to make up for leakage. These holes are stopped up by screws 75 n. The object of this valve is to regulate the speed of the descending elevator. The speed of the empty elevator is first regulated by turning the pin p farther in or out of the stopper, so that the opening k is moved a little into the 80 sleeve, leaving as effective opening only that portion of the opening k in the stopper that is below the top of the opening g. The spring l keeps the pin p resting on the shell s of the cylinder, leaving the greatest opening for the 85 empty elevator. This being done, the valve requires no more attention. If the elevator is loaded, the greater pressure in the cylinder forces the stopper h up by pressing under it through the opening o in the sleeve and forces 90 the stopper more into the sleeve, thus leaving less of the opening k effective. The rapidity of the descending elevator can therefore never become too great, for in that case the stopper would be pressed entirely into the sleeve, leaving 95 no opening at all for the oil, and bringing the elevator to a standstill.

This arrangement does away with the necessity of using brakes in connection with the hoisting machinery. In case loads are to be 100 lifted the weight of which varies but little the cylinder needs neither channel I nor valve.

All that is necessary is to bore a few holes in the piston to establish the connection between both sides of the cylinder.

This device is not only applicable to cable elevators, but also to piston or telescoping tube elevators, and is also applicable to any kind of hoisting and elevating cars, such as inclined cable, rack-and-pinion, or friction-clutch railways.

10. What I claim as new and of my invention is—

1. In an elevator having the guides A and the vertically-moving cage B, the cylinder H, attached to the cage, and having a passage 15 connecting its opposite ends, in combination with the piston L within the cylinder, the piston-rod G, and the pinion or other frictional contrivance constructed to engage a rack or other frictional surface upon the side of the 20 guides, substantially as herein described.

2. The combination, with an elevator-car and the rack C, attached to the ways of the eleva-

tor, of the cog-wheel D, engaging with said rack, of the piston L, connected with said cog-wheel D, and of a cylinder, H, containing a 25 liquid, and provided with an adjustable self-regulating valve, all substantially as herein shown and described, and for the purpose set forth.

3. The cylinder H, with its piston L, and the 30 passage I, connecting its opposite ends, in combination with the valve h and the sleeve f, intercepting the passage, and having the openings g, k, and o, and the spring l, substantially as and for the purposes described.

4. The cylinder H, with its piston L, the 35 passage I, connecting its opposite ends, and the automatic valve h, as shown, in combination with the regulating-screw p, substantially as herein described.
